corporation

Application August 25, 1932, Serial No. 630,421

13 Claims. (Cl. 98—39)

This invention has reference to heating and ventilating units and, particularly, relates to means, devices or apparatus for controlling, metering or measuring both recirculated and fresh air and indicating the amount of recirculated and fresh air to be or being, treated in the unit and delivered to the room of installation of the unit.

It is well known that legal requirements and local ordinances compel the use, in certain public buildings, such as school-houses, of heating and ventilating apparatus which will deliver to each room a definite number of cubic feet of fresh air per person. To meet the requirements, various apparatus and units have been devised; but, none has been able to constantly and fully meet the requirements in varying temperatures and outside conditions. Inlet and recirculating dampers have been variously controlled in the units, and various combinations of known means have been utilized; but, no satisfactory means, prior to my invention, have been found to furnish the necessary cubical supply of fresh air and deliver the same constantly, to the room of installation of the unit. And in no instance has it been possible, prior to my invention, in any system of heating and ventilation, to gage and ascertain the amount or volume of air passing through the unit and, at the same time, control the fresh air content of such volume under any and all outside weather conditions.

According to my invention, a controller has been provided, for heating and ventilating units, which performs the important function of controlling the amount of fresh outside air which is being supplied during a predetermined period to the room of installation of the unit, according to the mode of adjustment of the controlling means, and also the inlet damper of the unit. With my invention applied to a heating and ventilating unit, whether of the automatic or hand operated type, I am able to obtain efficacious operations and important functional results which will be fully disclosed hereinafter.

In order that my invention may be clearly understood I have provided drawings wherein:

Figure 1 is a view in front elevation of a heating and ventilating unit having my invention for automatically metering and controlling the amount of fresh air admitted to the unit applied thereto;

Figure 2 is a view in sectional elevation of one end of the unit shown in Figure 1;

Figure 3 is a view in front elevation, with parts broken out and in section, of my velocistat, that is, my instrument for metering and controlling,

and indicating the amount of fresh air admitted to the unit;

Figure 4 is a sectional view taken on the line 4—4 of Figure 3;

Figure 5 is a transverse sectional view taken on the line 5—5 of Figure 3;

Figure 6 is a fragmentary sectional view taken on line 6—6 of Figure 3;

Figure 7 is a fragmentary transverse sectional view taken on line 7—7 of Figure 3;

Figures 8 and 9 are transverse sectional views taken, respectively, on lines 8—8 and 9—9, of Figure 3;

Figure 10 is a wiring diagram of the apparatus;

Figure 11 is a view in front elevation of a unit, 15 similar to that of Figure 1, showing my hand-controlled means for admitting fresh air to the unit and for indicating or metering or measuring the amount of fresh air admitted;

Figure 12 is a view in sectional end elevation of 20 the unit shown in Figure 11;

Figure 13 is a view in front elevation, with parts broken out and in section, of my velocimeter, that is, my instrument for indicating or metering or measuring the amount of fresh air admitted 25 to a hand-operated damper unit;

Figure 14 is a view in elevation of one end of the velocimeter;

Figure 15 is a transverse sectional view taken on the line 15—15 of Figure 13;

Figure 16 is a vertical sectional view taken on the line 16—16 of Figure 13; and

Figure 17 is a schematic plan view illustrating the velocimeter as utilized in a central fan control system.

Referring to the drawings and particularly Figures 1 to 10, the reference numeral 20 designates the casing of a known form of heating and ventilating unit. Communicating with the lower part of the casing is a fresh air inlet 21, which is provided on its outer end (not shown) with the customary louvers and screen. The fresh air inlet leads into a part of the casing above the damper 26 termed the lower mixing chamber 22. Extending across the front of the unit and also in 45 communication with the chamber 22 is the recirculation opening 23 which is enclosed by a grille casing 24. Pivotetd at 25, in the chamber 22, is a damper 26 which, in one extreme position, closes the fresh air inlet 21 (see Figure 2) and in the 50 other extreme position closes the recirculating opening 23. In any of its intermediate positions, depending upon where the damper is located, the proportions of fresh air and recirculated air may be varied.

30

35

40

45

55

Situated above the lower mixing chamber 22 is the fan chamber 27. A pair of suction fans and casings 28 are positioned in this chamber and the fans are driven by a motor 29, Figure 1, 5 which is mounted between the fans. Air is drawn in through the eyes or ends 30 of the fans and is expelled through openings 31 in a partition 32 into the upper chambers.

Adjacent the bypass chamber 33 and separated 10 therefrom by a partition 34 is the heating chamber 35 in which is mounted the heating elements or radiators 36. Pivoted at the lower edge of partition 34 is a mixing damper 37. This damper may be operated by thermostatic or other suitable means; but, as said means form no part of the present invention, they are not illustrated. It will be apparent from an inspection of the drawings that, depending upon the position of the mixing damper 37, all the air may be directed 15 to the upper mixing chamber 38, through the bypass chamber 33, or through the heating chamber, or any desired proportionate amount, depending upon the temperature outside or inside the room, may be directed through the heating chamber and the bypass chamber and mixed 20 in the chamber 38.

The air passes through the mixing chamber 38 from whence it passes through an outlet opening 39 covered by a grille 40. The apparatus described up to the present time comprises a suitable type of heating and ventilating unit. There are different forms of heating and ventilating units, and it is to be understood that my invention hereinafter described is readily applicable 25 to all such known forms.

It is an important problem in the operation of heating and ventilating units to insure the proper amount of fresh air being admitted to the unit. In classrooms, where a large number of pupils 30 are gathered, it is essential for their good health to be able to control and readily ascertain the amount of fresh air entering the unit. Where only a few pupils are in the class-room, the amount of fresh air admitted to the unit may be 35 reduced materially and thus, particularly in cold weather, economies may be effected and the health of the students always guarded.

The instrument used for metering and automatically controlling the fresh air admitted to 40 the unit, is termed a velocistat. It is referred to generally by the reference numeral 41, Figures 1 and 2, and is shown in detail in Figures 3 to 9. The mechanism is carried by a frame comprising a base 42 and upstanding, supporting members 43, 44 and 45. Pivoted between the members 43 and 44 is a vane 46 in the form of a blade of considerable area and made of thin, light material so as to be very susceptible to air currents. The vane is secured to a pintle 47 45 which in turn is pivoted in anti-frictional cone bearings 48 and 49 mounted, respectively, in the members 43 and 44. The bearing 48 has threaded engagement with the member 43 so as to be adjustable, and when it is properly positioned is 50 held by a lock nut 50. Means are provided for perfectly balancing, or placing in a state of equilibrium, the vane 46; that is to say, the vane is so balanced that, when turned on its fine pivots, it will stay in any position it may be primarily set unless it is moved by a current of air. This balancing means comprises a pair of weights 51 and 52 mounted on that part of the vane below the pintle. Obviously, the same result 55 could be accomplished if the vane were of exactly the same area and weight on either side of

its pivot. However, to insure the proper area for contact with the air currents, the velocistat would be entirely too high and bulky if this arrangement were adopted. The weights approximately offset the additional weight of the vane 5 on the upper side of the pivots. However, in order to insure the extremely delicate balance that is desirable, the weights, which are mounted on either side of the lower part of the vane, are pivoted at 53, Figure 3, and may be moved 10 in an arcuate path. When the proper balance is obtained, the weights are held in position by a set screw 54 which passes through the arcuate slot 55 and has threaded engagement with the weight 52, (see Figure 5). 15

The vane 46 carries a contact finger 56, the function of which will be hereinafter described. An adjustable counterweight is provided to work in conjunction with the vane 46. The adjustable counterweight comprises a block 57 freely 20 mounted to swing independently on the pintle 47. The block terminates in a threaded stem 58, on which an adjusting nut 59 is threaded. A set screw 60 passing through the block is adapted to contact with the weight 52, Figures 3, 4, and 7, 25 which extends laterally beyond the slotted end of the vane 46.

From the foregoing it will be apparent that, depending upon the angular position of the vane, more or less effort or pressure will be required 30 to turn it. The adjustment of the counterweight may be very finely regulated by moving the nut 59 on the stem 58 and by positioning the set screw 60.

As shown in Figures 5 and 7, the counterweight 35 is so positioned that a current of air, being drawn or blowing in the direction of the arrow *a* in Figure 5, will have to be comparatively strong to shift the vane 46. As the vane is moved to the right, or clockwise, in Figures 5 and 7, the 40 counterweight 57 will exert less effort on the vane and, therefore, a smaller air velocity will shift the vane. The reverse of this is true if the vane is moved to the left in Figures 5 or 7, that is, as pressure is reduced on the vane, the counterweight will move the vane reversely. Walls 61 extend upwardly between the upstanding members 43 and 44 and act as shields to prevent the air currents engaging and influencing the vane below its pivot and thereby tending to 50 cause an unbalanced condition.

Secured to the upstanding member 44, on the side opposite the vane 46, is fixed a curved indicator or gage-plate 62, suitably graduated as at 63 in Figure 4. A pointer 65 is adapted to 55 traverse the gage-plate 62. Means, hereinafter described, are provided for moving the pointer and thereby indicating the setting of the velocistat which, in turn, controls the admission of fresh air into the unit and the amount thus 60 admitted. The pointer 65 is carried by an arm 66, which is pivotally mounted on a stud 67, supported on the member 44. The cone bearing 49 is formed in a reduced threaded portion of the stud 67, which passes freely through an opening 65 in the member 44 and the stud is rigidly held in position by a nut 68. A nut and washer 69 on the opposite end of the stud confine the arm 66, which is made of insulating material such as bakelite or hard rubber. In addition to the 70 pointer 65 arm 66 carries two contact members 70-70 (see Figure 6) which in turn have threaded therein contact screws 71-71 for co-operation with the contact finger 56 carried by the vane 46. The contact members 70 are held in posi- 75

tion in the arm 66 by nuts 72—72 cooperating with threaded extensions on the contact members, and screws 73—73, threaded into said extensions, function to retain leads which will be described hereinafter in connection with the wiring diagram. The contact finger 56 passes through a curved slot 74 in the member 44.

Means are provided for adjusting the position of the arm 66 and its pointer 65, shown particularly in Figures 4 and 9. The arm 66 carries a block 75 which is swiveled therein and has an internally threaded aperture and acts as a nut for the adjusting screw 76. This adjusting screw passes freely through another block 77 which is swiveled in the member 45, as indicated at 78 in Figures 3 and 4. The adjusting screw 76 has a flange 79 which engages one side of the swiveled block 77 and a collar 80 engages the opposite side of the swiveled block. Thus, longitudinal movement of the adjusting screw is prevented and, when it is rotated, the arm 66 will be moved in one direction or the other depending upon which way the adjusting screw is turned. The end of the adjusting screw beyond the flange 79 is squared as at 81 to accommodate a socket wrench for rotating the screw.

The operation, in connection with other parts of the invention, will now be described, and for this purpose particular attention is directed to Figures 1 and 2, and the wiring diagram of Figure 10.

The velocistat 41, through its electrical contacts 71a—71b and contact finger 56 will operate a reversing motor 82, in one direction or the other. The reversing motor, through suitable reduction gearing, well known to one skilled in the art, will move the arm 83 in one direction or the other. The arm 83 is connected by a link 84 with another arm 85 secured to the trunnion or pivot 25 of the damper 26. Thus, whenever the reversing motor is operated, the damper will be moved in one direction or the other.

The velocistat may be positioned in any part of the unit where it is in the path of an air stream. However, it would not be visible if it were placed in the fresh air inlet 21, or chamber 22, and more or less involved mechanism would have to be utilized to employ the control and display the reading. It has been found in practice that the most advantageous position in which to place the velocistat is in the recirculation opening 23, behind the grille 24 and substantially below the eye 30 of one of the fans 28. This position is indicated in Figures 1 and 2.

The suction fans deliver a predetermined amount of air through the outlet opening 40, at the top of the unit, into the room. By way of example, this amount of air might be said to be 1200 cubic feet per minute. As stated, this amount will be delivered constantly or as long as the fans are in operation and irrespective of the position of the damper 26. If the damper 26 were in the position as indicated in Figure 2, the 1200 cubic feet per minute would be recirculated air, drawn into the front of the unit at 23, from the room of installation. If the damper were moved to the other extreme position, the 1200 C. F. M. would be fresh air, drawn through the inlet 21 from the outside of the building. Obviously, in an intermediate position of the damper 26, the 1200 C. F. M. would be a mixture, proportionally, of fresh air and room air. The velocistat is so calibrated that when the pointer 65 is on the 200 graduation of the plate 62, 200 C. F. M. of room air is being drawn into the unit

and delivered together with 1000 C. F. M. of fresh air. When the pointer 65 is on the 400 mark, 400 C. F. M. room air and 800 C. F. M. of fresh air is being drawn into and delivered from the unit. When the damper 26 is automatically controlled and the velocistat is set for a predetermined air mixture, the unit will deliver this desired proportion of fresh air and room air, indefinitely, regardless of varying outside weather conditions. According to varying conditions of the outside atmosphere, the velocistat 41 and the inlet damper motor 82 will interact and cooperate to shift the damper 26 to cause it to maintain the desired conditions in the unit and in the room of installation of the unit. If the wind increases in velocity, while the damper 26 is open, the intake of fresh air will increase as compared with room air and the velocistat will immediately act to reverse the motor 82 and commensurately close the damper 26 at the fresh air inlet 21. If, subsequently, the room temperature becomes too low, the thermostat, controlling the inlet damper, will close the latter so as to permit all recirculated air to pass through the heating element 36, until the proper temperature is restored in the room of installation. Thus, in an automatic unit, the thermostatic control excludes all fresh air from the room of installation of the unit should the temperature of that room fall below the setting of the thermostat.

The amount of intake of fresh air and room air is controlled by the velocistat, and the shifting of the duplex damper (intake and recirculating) is motor controlled. The non-automatic unit is an alternative form and will be presently described.

The automatic control of the velocistat is brought about by the impact of the air, passing through the grille 23, upon the vane 46, which will move, according to variations in pressure, the finger 56 against one of the contact screws 71a—71b, close the motor circuit, and cause the motor 82, to function to shift the damper 26 the required amount to maintain the proper proportions of fresh air and room air entering the unit, and this without altering the required cubical air footage discharged from the top of the unit.

In Figure 10, the casings 20 of two heating and ventilating units, for example, are disclosed. There may be as many of these units as there are rooms in the school or building, although the invention is applicable to a single unit. The velocistats are indicated diagrammatically at 41 and the reversing motors at 82. The fan motors are also shown diagrammatically at 29; but, it is to be understood that their circuits are separate from the circuits controlling the reversing motors 82.

Each of the units is provided with a switch 86, see also Figure 1, at one end thereof, which may be set for fresh air or mixed air. When set for fresh air, the fresh air dampers 26 will open or be in the other extreme position from that designated in Figure 2. When set for mixed air, the fresh air dampers will be under control of the velocistats. Each of the units is also provided with a fan switch 87, on the outside of and at one end of the unit casing, as also shown in Figure 1, for controlling the fan motor circuits. The switchboard 88 is preferably positioned in the janitor's, or superintendent's, quarters. It carries a switch 89 which may be set to control the position of the fresh air dampers in all of the units. When this switch is in the "shut" position, or on

the contact 90, all the fresh air dampers in the units will be closed, or in the position of Figure 2, regardless of the setting of the switches 86 on the units. This is important because at night, or 5 on holidays when the rooms are unoccupied, it is essential that the fresh air dampers be closed to prevent the cold air entering the room and doing damage by freezing. When the switch 89 is in the open position, or on the contact 91, the 10 switches 86 on the units will govern the operation of the fresh air dampers as heretofore described.

A common switch (not shown) for controlling all the fan motors may also be positioned at the control station. The parts are so arranged and 15 wired that should the janitor open the common switch, or switches 87, which shuts off the fan motors, and neglect to throw the board switch 89 to the "shut" contact 90, the fresh air dampers will close if the switches 86 on the units are turned 20 to the "mix" contact, because the vane 46 of the velocistat will shift to motor reversing contact and cause the motor 82 to actuate the damper 26 to the position to shut out all fresh air. This is due to the fact that the stoppage of the fans 25 practically eliminates impact of air upon the vane of the velocistat, which vane thus returns to normal position. If the switches 86 on the units are set on the "fresh" contact, the dampers 26 will remain open until the temperature of the rooms 30 lowers to the setting of the thermostats indicated at 92, there being a thermostat for each unit. The thermostats may be set for example at 67° F., and will always close the fresh air dampers 26 regardless of the setting of either the 35 switches 86 on the unit or the switch 89 on the main control board.

Sometimes it happens that the operator or janitor desires to recirculate air in one or more rooms which are not occupied and at the same time leave steam in the radiators 36. In such case, he 10 shuts off the fan motor switch 87 at the unit and leaves the unit switch 86 on the "mix" contact. The fresh air damper 26, under control of the velocistat and motor 82, will then close against 15 the incoming air, as stated in the foregoing, regardless of the operation of the other units in the system.

Referring to the wiring diagram more specifically, the mains are indicated at 93 and 94. The 20 fan motors 29 are directly connected by leads 95 and 96 and through switches 87 with the high power mains 93 and 94. Leads 97 and 98, from the mains, run to a transformer 99, where the voltage is stepped down. A switch 100 is interposed between the transformer and the mains 93 and 94. The wires 101 from the transformer have 25 taps 102 which lead to one of the posts of the reversing motor which is grounded on the motor casing as at 103, the motor in turn being grounded to the unit casing 20 as at 103a. The leads 104 have taps 105 which lead to another of the posts on the reversing motor 82. A pilot light 106 is connected between the leads 101 and 104. Thus 30 current is supplied to the motors 82. Wire 107 runs from the "open" contact 91 of the switch and has taps 108 leading to posts on the reversing motor to drive the motor in a direction to open the fresh air damper when the circuit is completed by the velocistat. Lead 109 runs from the "shut" 35 contact 90 of the main switch 89 and has taps 110 leading to one of the contacts of the thermostats 92 and from there other leads 111 connect with wires 112 which lead to other posts on the reversing motor and to the "mix" contact 113 of the unit switches 86. Leads 114 from the switch

5 pole contact have taps 115 running to the other contacts of the thermostats 92 and from there through the fingers 116 of the thermostats to leads 117 which run to the contacts 11a of the velocistats. The leads 117 also have connections 10 118 with the "fresh" air contact 119 of the unit switches 86. Leads 120 connect the switch pole contacts of the unit switches with the other contacts 11b of the velocistats. The blades 46 of the velocistats which carry the contact fingers 56 are 15 grounded as indicated at 121, the heating and ventilating unit thus forming the other leg of the circuit.

If the gage 65 of the velocistat is set a trifle beyond 400, as indicated in Figure 4, the contact 15 finger 56 will engage the contact 11a and the fresh air damper will open until such time as a volume of air of somewhat more than 400 C. F. M. are being admitted through the recirculating opening. When this point is reached, the 20 contact finger 56 will be poised between the contacts 11a and 11b and remain there unless some outside increase in air velocity disturbs its equilibrium. The contact finger will then be forced against the contact 11b and the motor reversed 25 to close the fresh air damper a sufficient amount to again maintain the balanced condition.

Figures 11 to 16 illustrate a simpler form of my invention and one which is particularly applicable to hand-controlled heating and ventilating 30 units. The general arrangement of the unit illustrated in Figures 11 and 12 is similar to that shown and described in Figures 1 and 2, and the same reference characters are applied to similar parts, so it will not be necessary to enter into 35 a detail description thereof.

In this form of my invention, the volume of 40 room air as compared with fresh air, entering the unit, is indicated by a form of device which I have termed "velocimeter" to distinguish it from the "velocistat" or automatic form of my invention. The velocimeter is devoid of the 45 electrical contacts and is thereby greatly simplified. Instead of the damper 26 being controlled by a motor, as in Figures 1 and 2, a hand controller is used, as shown in Figures 11 and 12. A short arm 151 is secured on the inner end of the stud on which the handle 150 is mounted. A link 152 connects the arm 151 to another arm 153 secured to the pivot 25 of the fresh air damper 26. It will thus be apparent that as the control handle 150 is moved, the fresh air damper will be opened or closed allowing more or less 50 fresh air to enter the unit as compared with room air passing the device 154.

It is desirable to meter or actually ascertain the amount of fresh air entering the unit, and accurately indicate the same; so the velocimeter is employed and is located in the unit at the same point as the velocistat. The blade 46 and 55 its pintle 47 are pivoted in a similar manner. The same balance weights 51 and 52 are utilized, and the counterweighting means 57, 58, 59, and 60 are similar. However, the vane 46 carries an indicator 155 which passes through an opening 156, in the wall 44, and traverses the indicator plate 62 which is graduated in a similar manner to the same plate on the velocistat. Both the velocimeter and velocistat may be covered or partially covered by a protecting mesh as indicated at 157, in Figures 3 and 13. This is primarily to prevent children, in a schoolroom, from tampering with the instruments.

The fresh air damper 26 is manipulated by hand and when it is opened a certain amount, 75

the operator glances at the velocimeter and notes the amount of recirculated air being delivered to the unit. If this amount is too much, the damper is closed somewhat and the velocimeter again inspected. If an insufficient amount of fresh air is being delivered and these adjustments of the damper are continued, guided by the velocimeter, until the proper proportions of room and fresh air have been reached, the damper is then set. It is, of course, understood that, with the fans in operation, suction of air is caused through both the grille 24 and intake 21, and that the damper, actuated by hand, regulates the intake of air at front and back of the unit, and that the amount of intake of room air is immediately indicated on the gage-plate 62 of the velocimeter and quickly read with facility through the grille 24, enabling approximately accurate adjustments to be made, and the health and comfort of the occupants of the room are always guarded.

The velocistat and velocimeter may be used in numerous ways. For example, in Figure 17, a schematic illustration is given of the velocimeter applied to a central fan system. Therein the reference number 160 designates the chamber in which the fans and other apparatus are or may be housed. A series of conduits 161 may lead to separate rooms, or to heating and ventilating units, or to other devices requiring air. The conduits are provided with dampers 162, and beyond the dampers are located the velocimeters 154. The reading of the velocimeters is taken through openings which may be covered by a transparent material 163. It will be apparent that the dampers may be regulated in accordance with the amount of air required and the amount passing through the various conduits may vary and may be readily ascertained by reading the velocimeters.

The foregoing represents certain of many arrangements in which my invention may be used, and the system in use, or to be used, will determine the use of the devices disclosed. If it were desired to make the system, using a velocimeter, automatic in operation, the velocistat could be substituted for the velocimeter, in which event motors under control of the velocistats would be utilized to operate the dampers 162.

It will be understood, from the foregoing, that the calibrations on the segment 62, indicate specifically the volume of room air rushing into the inlet 23 through the grille 24 under suction from the rotary fans and knowing the volume of air which is being delivered through the grille 39, it requires merely an easy mental calculation to ascertain the amount of cold air rushing into the inlet chamber 22 to be mixed with the room air and discharged by the fans through one or more of the chambers above the latter and thence through the grille 39. It will be understood, however, that the calibrations can be reversed on the plate 62 so as to indicate directly the amount of fresh air entering the inlet chamber 22. In any event, the importance of both my velocistat and velocimeter is to control and ascertain the amount of fresh air being discharged into the room of installation through the unit in the predetermined volume which is so discharged. However, it will be further understood that the room air, in accordance with the forms of my invention disclosed herein is ordinarily the medium which is utilized for operating the vane of both the velocistat and velocimeter.

While I have shown and purpose claiming my velocistat and velocimeter in combination with a heating and ventilating unit, or heating and ventilating system, I desire it understood that other uses thereof may be made in the matter of measuring, indicating and controlling, automatically or otherwise, the volume of air or gases impinging upon or passing the same. And while I have, in the foregoing description, used the room air impinging upon the velocistat as a medium by which to gage or determine the amount of fresh air entering the unit, I may reverse this operation and calculation by utilizing the fresh air or outside air entering the unit as the medium by which to determine or gage the amount of room air entering the unit; or I may make the calibrations 63 indicate the amount of fresh air entering the unit, and thus by easy calculation determine the amount of room air entering the unit.

I desire it understood that I purpose claiming, for the foregoing reasons, my velocistat and velocimeter independently of any system or apparatus and in such terms as will necessarily involve and encompass the generic idea of means, operation and function of the two forms of my device.

Having thus described my invention, what I claim and desire to secure by Letters Patent is:—

1. A heating and ventilating unit having an air inlet chamber at or near its bottom, open at both front and rear, a single damper mounted in said inlet chamber in position to enable it to control both said openings, and means for actuating said damper including a device located at one of the openings and susceptible to operation by the power of the air entering said opening.

2. A heating and ventilating unit having an inlet chamber at or near its bottom having openings at its front and back, a damper mounted in said chamber and adapted to close the openings, and pneumatic means located at the front opening for controlling the position of the damper and simultaneously indicating the volume of air entering the unit through one of said openings.

3. A heating and ventilating unit having an air chamber at its bottom, provided with openings at its opposite sides for the admission of fresh and recirculated air respectively, a damper mounted in said chamber and adapted to close the openings; pneumatic means, operated by a part of the air volume entering the unit, for automatically controlling the position of said damper when the temperature of the room of installation of the unit is at or above a predetermined number of degrees, and thermostatic means for automatically actuating the damper to close the fresh air opening in the unit.

4. A heating and ventilating unit having an inlet chamber at or near the bottom, having openings at its opposite sides for the admission of fresh and recirculated air respectively, means for drawing the air through these openings, a damper shiftably mounted in said chamber, pneumatic means operated by a part of the air volume entering the unit for automatically controlling the position of said damper, said pneumatic means being adapted to automatically actuate the damper to close the fresh air opening when the aforesaid means for drawing the air through the unit openings has been made inoperative.

5. An instrument for metering, indicating and controlling the amount or velocity of air or gas passing through an opening substantially as outlined in claim 9, wherein a vane is provided with

a pointer and there are oppositely disposed electrical contacts insulated from the vane between which the pointer operates.

5 6. A device such as defined in claim 9, wherein the casing is provided with an indicating plate, has a pivotally mounted pointer adapted to travel relatively to the indicating plate, and the pointer is shifted relatively to a pair of electrical contacts.

10 7. A heating and ventilating unit having air inlets at back and front, and an air discharge at its top, a damper mounted between the two inlets and adapted to close the same alternately, a motor and connections to the damper for actuating the same, and means located at one of the inlets for actuating the motor including a pneumatic controller.

15 8. A heating and ventilating unit such as defined in claim 7 wherein the pneumatic controller is provided with means to open and close the motor circuit so as to reverse the same.

20 9. In combination with a heating and ventilating unit having an inlet opening, a pivotally mounted inlet damper, an instrument for metering the air admitted to the unit mounted in the inlet opening of the unit, and means actuated by the metering instrument and connected to the inlet damper for actuating the latter and for controlling the operation of the metering instrument.

25 10. A heating and ventilating unit having air inlets at back and front, and an air discharge at its top, a damper mounted between the two inlets and adapted to close the same alternately, a motor and connections to the damper for

actuating the same, and means located at one of the inlets for actuating the motor including a pneumatic controller having means causing it to open and close the motor circuit under the impulse of varying volumes of air entering the unit. 5

11. In combination, a casing of a heating and ventilating unit having a normally open recirculating inlet at its lower front, a damper for controlling the admission of air into said unit, and means for operating said damper, including 10 a device arranged at the said inlet and susceptible to and operated by the power of a part of the air volume entering the unit at said inlet.

12. A heating and ventilating unit having an air inlet chamber at or near its bottom open at 15 opposite sides, a single damper pivotally mounted in the bottom of the unit between said openings and adapted to control both thereof, operating mechanism for said damper, and a device for controlling the operation of the damper located 20 at one of the openings and having means susceptible to operation by the entering air, and connections between said device and the damper operating mechanism.

13. In combination, a casing of a heating and 25 ventilating unit having a recirculating opening at its lower front, and a fresh air inlet, means for effecting movement of a predetermined volume of air through said casing, and means controlled by the movement of air into the casing for 30 regulating the amount of fresh air of said volume passing through the casing.
